UNITED STATES PATENT OFFICE.

ARTHUR ROBERT KRAUSE, OF WOODHAVEN, NEW YORK, ASSIGNOR TO LION ELECTRIC MANUFACTURING CO., INC., A CORPORATION OF NEW YORK.

DESIGN FOR A LAMP-SOCKET STANDARD.

Application filed October 7, 1924. Serial No. 10,987. Term of patent 7 years.

To all whom it may concern:

Be it known that I, ARTHUR ROBERT KRAUSE, a citizen of the United States, residing at 3966 Fulton Street, Woodhaven, Long Island, county of Queens, city and State of New York, have invented a new, original, and ornamental Design for a Lamp-Socket Standard, of which the following is a specification, reference being had to the accompanying drawing, which forms a part of this application and illustrates my design applied to a lamp socket standard.

In the drawing, the single figure is a perspective view.

I claim:

The ornamental design for a lamp socket standard, as shown.
